UNITED STATES PATENT OFFICE.

CLARENCE W. MCKEE, OF PHOENIX, ARIZONA TERRITORY.

DESIGN FOR AN INHALER.

SPECIFICATION forming part of Design No. 25,858, dated August 4, 1896.

Application filed July 2, 1896. Serial No. 597,903. Term of patent 7 years.

To all whom it may concern:

Be it known that I, CLARENCE W. MCKEE, of Phoenix, in the county of Maricopa and Territory of Arizona, have invented and produced a new and original Design for an Inhaler, of which the following is a full, clear, and exact description.

Reference is to be had to the accompanying drawings, forming a part of this specification, in which—

Figure 1 is a side elevation of an inhaler embodying my new design, and Fig. 2 is a plan view thereof.

The design in its entirety comprises two similar members *a a*, joined by a broad loop *b*, which departs from the opposed sides of said members and is curved into semicircular

form. The members *a a* are oval and taper from their connected ends, and, further, the ends of the members *a* present foraminated surfaces *c c'*.

The leading feature of my design consists in the similar tapering members joined at one end by a loop.

Another feature resides in the oval form of the members *a a* in connection with the other features enumerated.

I claim—

The design for an inhaler, herein shown and described.

CLARENCE W. MCKEE.
